UNITED STATES PATENT OFFICE.

RICHARD MILLER, OF NEW BERLIN, OHIO.

DESIGN FOR A WEB-BUCKLE.

45,760.

Specification for Design.

Patented May 12, 1914.

Application filed March 16, 1914. Serial No. 825,175. Term of patent 7 years.

To all whom it may concern:

Be it known that I, RICHARD MILLER, a citizen of the United States, residing at New Berlin, in the county of Stark and State of Ohio, have invented a new, original, and ornamental Design for Web-Buckles, of which the following is a specification, reference being had to the accompanying drawing, forming part thereof.

In the drawings, Figure 1 is a front perspective view of a web buckle embodying my new design. Fig. 2 is a rear perspective view of the same.

I claim:—

The ornamental design for a web buckle, substantially as shown.

RICHARD MILLER.
